SPRINKLER HEAD FOR FIRE EXTINGUISHING SYSTEMS

Cesar J. Cid, Montreal, Quebec, Canada

Application February 20, 1939, Serial No. 257,556
In Canada January 17, 1939

13 Claims. (Cl. 169—37)

This invention relates to improvements in sprinkler heads for fire extinguishing systems and the primary object of the invention is to provide a sprinkler head which will open automatically to 5 permit egress therefrom of water or other fire extinguishing fluid when the temperature of the surrounding atmosphere rises to a predetermined degree and which will close automatically to stop egress of fire extinguishing fluid when the temperature of the surrounding atmosphere falls to a 10 predetermined degree.

A further object is to provide a sprinkler head in which the operation of temperature responsive means governing the opening and closing of the 15 head is not affected by fire extinguishing fluid flowing in or from the head.

A still further object is to provide a thermostatically controlled sprinkler head which will open and close quickly.

20 Another object is to provide a sprinkler head in which the closure member is protected from foreign matter which might interfere with proper working of the head.

Still another object is to provide a sprinkler 25 head in which the temperature responsive element and all working parts are shielded from mechanical injury which might interfere with the proper working thereof, the temperature responsive element being nevertheless exposed most advantageously to the surrounding atmosphere.

An additional object is to provide a sprinkler head of simple, durable and efficient construction.

Various other objects and the advantages of the 35 invention may be ascertained from the following description and the accompanying drawing.

The sprinkler heads at present in general use all have the great disadvantage that they are incapable of closing or being closed once they have opened. As result, it happens not infrequently 40 that, after a fire has been extinguished, the water or other fire extinguishing fluid continues to flow from the sprinkler until the supply is cut off and thereby occasions much needless damage to a building and its contents. Also, the sprinkler heads at present in general use throw out the closure and locking means thereof when they 45 operate and the head is therefore incapable of reuse until these parts have been replaced. Until this replacement is effected the water must be shut off and part or all of the system thus rendered inoperative for its purpose. If a fire should 50 recur during this period there is no protection. Thermostatically controlled sprinkler heads have been proposed but are unsatisfactory by reason of 55 slow or imperfect opening and closing.

Broadly speaking, the present invention consists in providing a sprinkler head having a closure member mechanically urged to closed position and governed by a thermostat arranged to open or initiate opening of the head when the temperature of the surrounding atmosphere rises to a predetermined degree and to permit or cause closing thereof when the temperature of the surrounding atmosphere falls to a predetermined degree.

More particularly the invention consists in the combination and arrangement of features disclosed in the present description or in the accompanying drawing, together with all such modifications thereof or substitutions of equivalents 15 therefor as are within the scope of the appended claims.

In the accompanying drawing which illustrates an embodiment of my invention now preferred together with a modification thereof, but to the details of which embodiments the invention is not confined:

Fig. 1 is an elevation of a sprinkler head embodying that form of my invention now preferred.

Fig. 2 is a sectional view on the line 2—2 of Fig- 25 ure 1.

Fig. 3 is a section on the line 3—3 of Figure 2.

Fig. 4 is a view similar to Figure 2 illustrating various modifications of structure.

Referring more particularly to the drawing, 11 30 designates the hollow body of a sprinkler head which is conveniently, though not necessarily, of cylindrical form and provided with an internal transverse member 12 which is preferably a spider serving to guide and support parts hereinafter 35 referred to. The body is provided with a hollow threaded neck 15 forming an inlet passage for the body, the neck being adapted for attachment to a pipe supplying water or other fire extinguishing fluid. The upper part of the body may be of reduced diameter, as shown at 16, and is provided with an internal shoulder 17 which may be formed by provision of a flange 18 or any other suitable means. The flange 18 or any equivalent structural feature forming the shoulder 17 is in- 40 internally threaded to receive an externally threaded seat ring 19 having a seat surface 20 which may be flat or otherwise formed. The seat ring may extend some distance above the seat or may terminate at any different level and is pro- 50 vided with means, such as the slots 21, for engagement with a suitable tool to screw the seat ring into the body and against the shoulder 17.

The upper part of the body may be provided with a nozzle member 22 screw-threaded into the 55

body or attached thereto in any other suitable way, permitting of the insertion and retention of a diaphragm 23 of paper or other suitable readily rupturable material as by clamping between the body and the nozzle member. The nozzle member is provided with a yoke 24 or other suitable structure supporting a deflecting plate 25 of any usual or suitable form in axial alignment with and spaced relation to the opening 26 of the nozzle for the purpose of distributing fire extinguishing fluid over a considerable area, as is well understood.

The member 12 is provided with an opening 27 disposed in axial alignment with the seat ring 19. A valve or closure member 28 of any suitable form is provided upon the seat and has a depending stem 29 of an external diameter substantially less than the internal diameter of the seat ring, whereby an annular passage 30 is established between the valve stem and the inner surface of the seat ring through which a fire extinguishing fluid may flow when the closure member is lifted from its seat. The stem 29 is provided with wings 31 fitting loosely within the seat ring for the purpose of keeping the valve and stem centered in the ring, as will be well understood, but the wings may be omitted if desired. The stem is provided with an extension 32 which passes freely through the opening 27 to approximately the lower end of the body, where it carries a shoe 33 which may be saucer-shaped as shown. A helical spring 34 is mounted in compression between the shoe 33 and the member 12 and surrounds the spindle extension 32. One end of this spring is held co-axial with the spindle by the saucer-shaped formation of the shoe, while the other end of the spring is held properly centered by a boss 35 on the member 12.

The end of the body opposite the deflector 25 is provided with a cap 36 which may be screwed thereon or attached in any other suitable manner and is formed with a plurality of openings 37 giving free access to the interior of the cap.

A temperature responsive element 38, preferably of the volatile liquid containing bellows type, is mounted within the closure cap and is preferably attached thereto by means of a threaded stud 39 on the surface of the thermostat remote from the spindle. Any other suitable type of temperature responsive element may be used. The opposite surface of the thermostat is separated from the shoe 33 by a thin corrugated flexible metal diaphragm 40 interposed between the thermostat and the shoe for the purpose of closing the lower end of the head and normally retaining the fluid pressure of the system in the head. In the drawing the thickness of the diaphragm has been greatly exaggerated. The diaphragm 40 is preferably mounted in a carrier ring 41 threaded into or otherwise suitably secured to the body and is connected to the spindle by any suitable means, such as a nut 42. The thermostat is thermally insulated from the diaphragm, at points where force is transmitted from one to the other, by a washer 43 of suitable insulating material and is elsewhere insulated by the air space between them. The effective area of the diaphragm is considerably greater than the effective area of the closure member.

The member 12, which is a spindle guide and spring abutment, may be omitted and the spring extended to abut the part 18 or other suitable part, the spindle being held centered in the body by the diaphragm and the closure member, as shown in Figure 4.

While a valve closure spring has been shown and described, it will be understood the spring may be omitted and the diaphragm used may be of such stiff construction and resilient character as to normally perform the functions of the spring. Also, a spring and a resilient spring acting diaphragm may be used in conjunction. Alternatively, the thermostat may be of such stiff construction as to perform the function of the spring or of a resilient diaphragm and may be then directly connected to the spindle, as shown in Figure 4. Such a thermostat may be used in conjunction with a spring or spring diaphragm.

The sprinkler head is designed to be normally installed in the position indicated in the drawing, that is, with the deflecting plate 25 at the top and the thermostat at the bottom, but it will be understood it may be installed otherwise, for example, in inverted position or axially inclined. In any position, the openings 31 allow the surrounding atmosphere free access to the thermostat and, in the normal position of the head, the thermostat is directly in the path of hot air rising from a fire in the vicinity of the head. The type of thermostat used is preferably the metallic bellows type charged with a highly volatile liquid, such as ether or a mixture of ether and acetone. Such a thermostat, when heated, exerts a very powerful expansive action by reason of volatilization of the liquid therein and thrusts against the valve stem to open the valve against the action of the spring and against any fluid pressure on the diaphragm. When the valve is opened, fluid which is confined in the head and in the system to which the head is connected escapes past the valve and through the opening 26, rupturing the paper diaphragm 23 in its passage. The solid stream of liquid emerging through the opening 26 impinges the deflecting plate 25 and is thereby deflected downwardly and outwardly and distributed over a large area in the well known manner. The thermostat being, when the head is in normal position, under the body and surrounded by the cap 36, is completely shielded from the fluid escaping through the head and any chilling of the thermostat is avoided, so that the head remains open as long as the temperature of the surrounding atmosphere is at or above a predetermined degree. When the temperature of the surrounding atmosphere falls sufficiently, the pressure of the vapour in the thermostat falls and enables the thermostat shell to contract, thus permitting the spring or the diaphragm or the thermostat, separately or in combination according to the construction, to seat the closure member and stop the egress of fire extinguishing fluid from the head. Even if the head is installed in inverted position, the thermostat is shielded by the body of the head and the cap 36 from escaping fluid and is thereby prevented from being chilled.

It will be observed that the effective area of the diaphragm 40 exposed to the pressure within the system is much greater than the effective area of the closure member 28 similarly exposed, whereby the directly connected closure member and diaphragm constitute an unbalanced valve tending, when closed, to be held closed by pressure in the system, notwithstanding that the closure 28 is outwardly opening and irrespective of any force exerted by any or all of the diaphragm, spring and thermostat shell tending to hold the closure 28 on its seat. When the thermostat is heated, pressure builds up therein to a point where the expansive force is sufficient to overcome the unbalanced fluid pressure on the diaphragm and the

resistance of the diaphragm (and spring if any) to flexion and the closure member is lifted from its seat. The initial lifting of the closure member causes a sudden drop in fluid pressure within 5 the head so that the unbalanced fluid pressure on the diaphragm is suddenly reduced, thus enabling the pressure in the thermostat to complete opening of the closure member very quickly, the expansive force of the thermostat being at that instant much greater than the flexion resistance of 10 the diaphragm (and spring if any). In other words, the unbalanced fluid pressure on the diaphragm holds the thermostat against expansion until the expansive force therein has built up to a 15 degree considerably in excess of the inherent resistance of the diaphragm (and spring if any) and the force of the thermostat is then suddenly released against the diaphragm and spring by sudden release of the unbalanced fluid pressure in the 20 head.

The converse occurs in the closing of the head. As the thermostat cools off it contracts and allows the reflex action of the diaphragm (and spring if any) to draw the closure member toward its seat. 25 When the closing movement is sufficient to cause a throttling of the fluid flow, pressure commences to build up in the head and acts upon the diaphragm to assist the reflex action thereof (and of the spring if any) to force the closure member 30 quickly onto its seat.

The springs used will be of strength according to the fluid pressure in the system and adequate to close the valve and maintain the same tightly closed either alone or with the assistance of the 35 unbalanced fluid pressure on the diaphragm, and the same applies to the thermostat shell and diaphragm when either or both of these are used to perform the function of the spring. The thermostats will have capacity to flex the spring and 40 the diaphragm to open the valve.

The sprinkler heads according to this invention may be used equally well on either wet pipe or dry pipe systems.

While the illustrated embodiments of the invention are characterized by an arrangement of the closure member, diaphragm and thermostat in axial alignment, it will be understood the invention is not thus limited as other arrangements may be resorted to and are contemplated.

Having thus described my invention, what I claim is:

1. A sprinkler head for fire extinguishing systems comprising a body, a valve therein, spring means normally holding said valve closed, a thermostat operatively connected to said valve to initiate valve opening and means for holding said thermostat inoperative to open the valve until activating pressure in the thermostat is sufficiently in excess of the flexion resistance of 55 said spring means to ensure quick full opening of the valve, said means comprising a member interposed between the thermostat and fluid in the body and operatively connected to said thermostat to transmit pressure of said fluid to the 60 thermostat.

2. A sprinkler head for fire extinguishing systems comprising a body, a valve therein, a thermostat subject to fluid pressure in the body independently of fluid pressure on said valve and 65 thereby restrained from expansion, means for transmitting expansive movement of the thermostat to the valve to partially open same and release fluid pressure in the body whereby the thermostat is freed for rapid expansion to quickly 70 open the valve.

3. A sprinkler head for fire extinguishing systems comprising a body, an unbalanced valve structure in the body including an outwardly opening closure member for the body and a second member within the body spaced from and 5 positively connected to said closure member, means for admitting fluid into the body between said closure member and said second member, the fluid pressure effective area of the second member being greater than the like area of the 10 closure member, whereby the closure member is normally held in closed position by fluid pressure within the body and a thermostat operatively connected to said valve and adapted to overcome the unbalanced fluid pressure and open 15 said valve.

4. A sprinkler head for fire extinguishing systems comprising a body and an unbalanced outwardly opening outlet valve means therefor including operatively opposed effectively unequal 20 portions exposed to fluid pressure in the body, the lesser of which portions constitutes the valve closure, whereby said valve means is normally held in closed position by fluid pressure in the body acting on said valve means, and a thermostat operatively connected to said valve means to open same and adapted upon predetermined 25 thermal activation to develop pressure at least up to the unbalanced pressure of fluid in the body acting on said valve means, whereby upon relief 30 of fluid pressure in the body the thermostat will open the valve quickly.

5. A sprinkler head for fire extinguishing systems comprising a body, an outwardly opening valve therein, means in the body connected to 35 said valve and adapted to be directly acted on by fluid pressure in the body in opposition to fluid pressure on said valve to hold the valve normally closed, and a thermostat carried by the body and operatively connected to said valve to 40 open same against the fluid pressure on said means.

6. A sprinkler head for fire extinguishing systems comprising a body, an outwardly opening valve therein, a thermostat operatively connected 45 to and arranged to open said valve and hold the same open during persistence of predetermined temperature conditions, valve closing means operatively connected to said valve and exposed to fluid pressure in the body and including 50 spring means to initiate valve closing and fluid pressure actuated means operatively connected to said valve and effective to close the valve upon increase of fluid pressure in the body due to partial closing of the valve by the spring means. 55

7. A sprinkler head for fire extinguishing systems comprising a body, having a fluid inlet intermediate its ends, an outlet valve normally closing one end of the body, a flexible diaphragm permanently closing the other end of the body, 60 a thermostat outside the body arranged to thrust inwardly on said diaphragm, and means extending between the diaphragm and valve to transmit thrust of the thermostat to said valve to open same. 65

8. A sprinkler head for fire extinguishing systems comprising a body, an outwardly opening valve for said body, a thermostat mounted on the body for opening said valve and operative connection between the valve and thermostat including a flexible diaphragm mounted on the body, one of said thermostat, diaphragm and connection including spring means adapted to 70 close the valve.

9. A sprinkler head for fire extinguishing sys- 75

- tems comprising a body having a fluid inlet intermediate its ends, an outwardly opening valve normally closing one end of the body, a flexible diaphragm closing the other end of the body, means 5 operatively connecting said valve and diaphragm, a spring acting on the valve to urge the same to closed position and a thermostat outside the body mounted thereon and arranged to thrust against the diaphragm with valve opening effect.
- 10 10. A sprinkler head for fire extinguishing systems comprising a body, an outwardly opening closure valve for said body, a resilient diaphragm exposed to fluid pressure in the body, connection between the diaphragm and valve arranged to 15 urge the valve to closed position by reason of the resiliency of the diaphragm and the fluid pressure thereon, and a thermostat operatively connected with said valve to open same.
11. A sprinkler head for fire extinguishing systems comprising a hollow body adapted for connection to a source of fire extinguishing fluid and having a fluid egress aperture, a valve in said head disposed outwardly of said aperture and adapted to control egress of fluid from the aperture, spring means arranged to hold the valve 25 normally closed against pressure of fluid in the head, temperature responsive means carried by the head adapted and arranged to open said valve against the action of said spring means upon 30 predetermined rise in the temperature of the surrounding atmosphere and to permit closing of the valve by said spring means upon predetermined fall in the temperature of the surrounding atmosphere.
- 35 12. A sprinkler head for fire extinguishing systems comprising a hollow body open at its opposite ends and having means for communicating the interior thereof with a source of fire extinguishing fluid, a valve seat surrounding the opening at one end of the body, a valve disposed outwardly of and adapted to said seat and including a stem extending toward the second end of the body, said stem having thrust receiving means at the free end thereof, a spring surrounding the stem and in compression between said thrust receiving means and an inner surface of the body adjacent said valved opening, a fluid pressure 10 thermostat carried by the body in alignment with said valve stem and a flexible diaphragm closing the second end of the body and interposed between and engaging both said stem and said thermostat. 15
13. A sprinkler head for fire extinguishing systems comprising a hollow body open at its opposite ends and having means for communicating the interior thereof with a source of fire extinguishing fluid, a valve seat surrounding the opening at one end of the body, a valve disposed outwardly of and adapted to said seat and including a stem extending toward the second end of the body, a flexible diaphragm closing the second end of the body and engaging said stem, a spring arranged to urge the valve against its seat, a fluid pressure thermostat carried by the body outwardly of and in contact with said diaphragm, a nozzle extension at the first named end of the body having an outlet aperture, a fragile diaphragm disposed between said valve and said nozzle outlet aperture, and a fluid deflecting member carried by the nozzle in alignment with and spaced outwardly from the fluid egress aperture thereof. 20 25 30 35
